 30, 1946, Serial No. 693,884. In France Septem-
 ber 3, 1941

12 Claims. (Cl. 60—13)

1

The present application, which is a continuation of my U. S. patent application Ser. No. 420,432, filed November 25, 1941, now abandoned, the latter being a continuation in part of my U. S. patent application Ser. No. 182,865, filed December 31, 1937, now abandoned, relates to free piston motor-compressors, that is to say machines including at least one motor part and at least one compressor part, and the reciprocating element or elements of which move with a length of stroke which is variable within certain limits, at least the main portion of the air compressed by the compressor part of the motor-compressor serving to feed a receiver, for instance a compressed air reservoir, an air turbine, and so on, distinct from the motor-compressor itself.

Said motor-compressors which deliver compressed air directly from the compressor cylinder or cylinders thereof to the outside of the motor-compressor must not be confused with free piston auto-generators wherein the whole of the air compressed by their compressor part flows through the motor cylinder for scavenging this cylinder and mixing with the combustion gases thereof, this gaseous mixture fed from the motor cylinder of the auto-generator constituting the final product of the same.

Among the motor-compressors thus defined, it is necessary to make a distinction between those in which both the outward and the inward strokes are produced by the combustion of fuel in a motor element, these machines therefore having a double action motor system, and those in which some of these strokes, for instance the outward strokes are produced by the combustion of fuel in a motor element, while the inward strokes are produced by elastic means, in particular by pneumatic cushions capable of storing up, during the outward strokes, a certain amount of energy which is subsequently restored to the free pistons for producing their inward strokes. In this latter case, the machines have a single action motor system.

The invention is more especially, although not exclusively concerned, among these machines, with those having a single action motor system.

The principal object of the invention is to provide a free piston motor-compressor capable of undergoing great load variations, corresponding either to pressure variations of the air delivered to the outside of the machine, or to variations of the amount of air supplied on every piston stroke obtained by varying the length of stroke, or to both variations at the same time.

2

Preferred embodiments of the present invention will be hereinafter described, with reference to the accompanying drawings, given merely by way of example, and in which:

5 Fig. 1 is a diagrammatical view of a free piston motor-compressor made according to a first embodiment of the present invention;

Fig. 2 shows a diagram illustrating the working of this machine;

10 Fig. 3 is a view, similar to Fig. 1, showing a second embodiment of the invention; and

Fig. 4 is a view, similar to Figs. 1 and 3, showing a third embodiment of the invention.

In the following description, it will be supposed that the invention is applied to the case of a free piston motor-compressor having a single action motor part which works on the two-stroke principle.

Concerning the general construction of the 20 motor-compressor, it is of any suitable known type. For instance, according to the embodiment illustrated by Figs. 1 and 3, it includes a motor cylinder 1 cooperating with two pistons 2¹ and 2², reciprocating in opposed directions, and 25 adapted to uncover, when nearing the ends of their outstrokes, inlet ports 3 and exhaust ports 4.

One of these motor pistons, for instance piston 2¹, is associated with a compressor piston 5 moving in a cylinder 6, this last mentioned piston ensuring, through its outer face, in the chamber 6¹ of said cylinder 6, the compression of the air to be produced by the motor-compressor and fed to the outside thereof, while the inner face of 35 piston 5 compresses, in the chamber 6² of the same cylinder, the air to be fed to a fluid-tight casing 7 surrounding motor cylinder 1.

The other motor piston, to wit 2², is rigid with a piston 8 moving in a cylinder 9 and which encloses, in this cylinder, an air cushion which stores up, during the outward stroke of the motor pistons, a certain amount of energy, which is given back to the pistons during their inward strokes, thus permitting said inward strokes to 45 take place.

The reciprocating structures 2¹—5, on the one hand, and 2²—8, on the other hand, are interconnected by synchronizing means, consisting, for instance, of a lever 10 oscillating about a 50 fixed axis 11 and connected at its ends, through connecting rods 12, with the two reciprocating structures, respectively.

I provide, for the feed of fuel to the motor cylinder 1, an injection pump or the like 13, controlled by one of the reciprocating structures

through a system of levers 14, and the quantitative regulation member 15 of which is operated, for instance, in response to variations of the pressure of compressed air in reservoir 16 fed by the chamber 6¹ of the compressor cylinder 6. Pump 13 is connected through a conduit 17 with the injector 18 which opens into motor cylinder 1.

In a motor compressor of the kind above described, the maximum power is limited, on the one hand, by the power of the motor part thereof, and, on the other hand, by the weight of air which can be introduced into the main chamber 6¹ of the compressor cylinder.

In order to increase the power of a given motor-compressor of this type, it is necessary to supercharge both said chamber and the motor cylinder.

Considering more particularly the supercharging of the motor cylinder, if the air to be fed to said cylinder for scavenging and combustion purposes were merely compressed by the inner face of compressor piston 5, it would be difficult to obtain high value and/or important variations of the pressure of said air.

On the other hand, in the case of a two-stroke engine, the utilization, for compressing the feed and scavenging air, of a blower driven by gas turbine feed with the exhaust gases issuing from the motor cylinder would be generally insufficient for obtaining the necessary air pressures, in view of the fact that the exhaust gases issuing from such an engine do not contain a sufficient amount of energy.

In order to avoid these drawbacks, I supercharge chamber 6², in which the inner face of piston 5 compresses the feed and scavenging air to be fed to the motor cylinder, by means of a blower 19 which may also serve to supercharge the main chamber 6¹ of the compressor part of the machine (see Fig. 1). This blower 19 is driven by a gas turbine 20 fed with the exhaust gases passing through the exhaust part 4 of the motor cylinder 1 into the exhaust conduit.

The discharge pressure of blower 19 is regulated by the variations of power of exhaust gas turbine 20, the power of which decreases when its inlet area increases for the following reasons:

When the input pressure of turbine 20 increases, blower 19 delivers air at a higher pressure to compressor unit 5-6². The motor unit 1-2¹-2² is therefore supercharged at a higher pressure and the number of reciprocations per unit of time of pistons 2¹-2² slightly increases, so that the mass of gases flowing through turbine 20 per unit of time slightly increases. But experiments have taught that this increase is very small and that, for practical purposes, the weight of gases flowing through turbine 20 can be considered as constant when the input pressure of turbine 20 varies.

On the other hand, it is known that for a turbine the output of which opens into the atmosphere, i. e. a medium at constant pressure, which is the case in the present instance, and through which the rate of flow by weight of the exhaust gases remains practically constant, which, as above explained, is also the case, the power delivered by said turbine is the higher as the input pressure is higher. And it is perfectly clear that when the inlet area of the turbine is reduced, the pressure of the exhaust gases; which are compelled to flow through this area is increased.

As shown by Fig. 1, exhaust gas turbine 20 is fitted with three inlet conduits 21¹, 21², 21³ controlled by a slide valve 22 rigid with a piston 23 movable in a cylinder 24. Piston 23 is subjected, on one of its sides, to the action of a spring 25, of suitable strength, which tends to apply said piston against abutment 26. The position of this abutment 26 is chosen in such manner that the inlet area of exhaust gas turbine 20 is minimum when piston 23 is applied against said abutment, and this is the position shown by Fig. 1.

The other face of piston 23 is subjected to the action of the pressure existing in reservoir 16.

When this pressure increases above a given value, it produces a displacement of piston 23 toward the right and, consequently, an increase of the inlet area of turbine 20, which, as above explained, corresponds to a reduction of the power of said turbine.

Preferably, I provide, on the exhaust pipe leading out from port 4 a branch pipe 27 opening into the atmosphere and controlled by a valve 28, which, for certain conditions of operation, permits of discharging a certain portion of the exhaust gases directly into the atmosphere without passing them through turbine 20.

It follows that, when the power of turbine 20 is maximum, and consequently when the load of the motor-compressor is maximum, the pressure in reservoir 16 is lower than that which exists therein when the machine is running on no load or with a low rate of delivery of the compressor. These two pressures determine the limits of regulation of the machine in question.

In the diagram of Fig. 2, I have shown, in solid lines and in dotted lines respectively, two different ways of operation of the motor-compressor, the difference between these methods of operation being due to different adjustments of the control device of turbine 20.

In the diagram of Fig. 2, the abscissas are the pressures existing in reservoir 16, while the ordinates represent, on the one hand, the rates of delivery Q into the main chamber 6¹ of the compressor cylinder and, on the other hand, the delivery pressures p¹ of blower 19. The regulation zone thus ranges between the reservoir pressure p^a corresponding to the machine running on maximum load and the reservoir pressure p^b corresponding to the machine running on no load.

As it results from the diagram of Fig. 2, the rate of delivery Q of the compressor cylinder is maximum when the load is maximum, while it is minimum, or even equal to zero, when the load is zero.

According to the first of the two above mentioned methods of operation, the power of turbine 20, and consequently the compression obtained by means of blower 19, gradually decreases from the maximum value thereof (corresponding to a pressure p^a in the reservoir 16) to the value when running on no load (corresponding to pressure p^b in the reservoir 16).

When running on no load (maximum value p^b of the pressure in reservoir 16), the turbo-blower system 20-19 therefore delivers but little work and the feed pressure to chambers 6¹ and 6² is but little higher than the atmospheric pressure. When the amount of air withdrawn from reservoir 16 exceeds a given value, the drop of pressure in this reservoir produces a reduction of the inlet area of turbine 20, due to a displacement of slide valve 22, which corresponds to an increase of the pressure in the

exhaust pipe of the motor and therefore to an increase of the power of the turbo-blower system and of the feed pressure to the chambers 6¹ and 6² of the compressor.

When the regulation takes place according to the modifications illustrated, in the diagram of Fig. 2, by the dotted lines, I obtain a gradual variation of the feed pressure p^1 from the blower within limits corresponding, on the one hand, to the maximum load of the motor-compressor and, on the other hand, to an intermediate load (for which the value of the pressure in reservoir 16 is p^0), while the feed pressure obtained from the blower remains substantially constant, at a value but little above atmospheric pressure, for values of the load ranging from this intermediate value to zero.

When the feed pressure obtained from blower 19 is close to the atmospheric pressure, the loss of power in the motor-compressor due to the working of the turbo-blower unit is practically equal to zero and can therefore be considered as negligible.

The embodiment of the invention that is illustrated by Fig. 3 of the drawings differs, concerning the supercharging of the chambers 6¹ and 6² of compressor cylinder 6, from the embodiment illustrated by Fig. 1, particularly by the fact that the circuit of the air compressed in the main chamber 6¹ of the compressor is wholly separate from the circuit of the feed and scavenging air intended for the motor cylinder and which passes through the chamber 6² of the compressor cylinder.

In the embodiment of Fig. 3, blower 19 feeds air only to the chamber 6² of the compressor from which feed and scavenging air is supplied to the motor cylinder. As for the main chamber 6¹ of the compressor it is fed from the outlet of a turbine 29 which is driven by compressed air coming from said chamber 6¹ (after passage through reservoir 16 as shown by the drawing), the air delivered by the turbine 29 being still under a pressure above atmospheric pressure and acting to supercharge the chamber 6¹. Therefore, this last mentioned air circuit is a closed circuit. The mean pressure in this circuit is regulated by means of a slide valve 30 which connects conduit 31, interposed between the discharge of turbine 29 and chamber 6¹, either with a source of air under pressure such, for instance as a compressed air reservoir 32, or with the atmosphere, in order thus to decrease or to reduce the weight of air present in this circuit.

In order simultaneously to regulate the power of the turbo-blower unit 20—19, the right hand side of piston 23 is subjected to the action of the pressure existing in said conduit 31 (as shown by the drawing).

Slide valve 30 may be operated either manually or automatically, for instance by the speed governor of turbine 29.

Of course, the variations of the inlet or discharge pressure of the air compressed respectively in compressor chambers 6¹ and 6² necessitate a suitable regulation of the return energy of the reciprocating structures of the motor-compressor.

This necessity results from the fact that this return energy, the greatest part of which is supplied by pneumatic accumulators 9, serves to produce compression work not only in the motor cylinder but also in compressor chamber 6².

In the embodiment shown by Fig. 1, as the

feed pressures of both of the compressor chambers 6¹ and 6² are equal, it suffices to operate the control device 34 of pneumatic accumulator 9 either by the inlet pressure of said compressor chambers, or by one of the discharge pressures of said chambers.

On the contrary, in the embodiment shown by Fig. 3, preferably, I operate this control device of the accumulator in accordance with the value of the inlet or discharge pressure both in main compressor chamber 6¹ and in the other compressor chamber 6².

Furthermore, in both cases, the accumulator control device must be controlled in accordance with the value of the mean pressure in accumulator 9 itself.

The return energy of pneumatic accumulator 9 is varied by increasing or decreasing the weight of air entrapped in said accumulator. In order to obtain this increase, the accumulator 9 is connected, through the control device in question, with a source of air under pressure, for instance with the reservoir 16 which contains the air compressed in chamber 6¹, while, in order to obtain a reduction of the weight of the air cushion entrapped in accumulator 9, this accumulator is connected, through said control device, for instance with the atmosphere.

For this purpose, in the embodiment illustrated by Fig. 1, I provide control device 34 with a slide valve 35 adapted to occupy different positions such that:

(a) It may keep accumulator 9 closed (position of the slide valve shown by Figs. 1 and 3); or

(b) It may connect cushion of air 9, through conduits 36 and 37 with reservoir 16; or again

(c) It may connect the same cushion, through conduits 36 and 38, with the atmosphere.

Slide valve 35 is made rigid with two pistons 39 and 40 movable respectively in cylinders 41 and 42.

Piston 39 is subjected to the opposed actions of a spring 43 acting on one side thereof and of the mean pressure existing in accumulator 9, acting on the other side of said piston. The mean pressure in question is transmitted to cylinder 41 through a calibrated conduit 44 extending between said cylinder and conduit 36.

Piston 40 is subjected to the action of the mean pressure existing in casing 7, owing to the provision of a calibrated aperture 45, this mean pressure being substantially equal to the discharge pressure in chamber 6².

Finally, I provide, in conduit 37, a check valve 46 intended to prevent a flow of air from accumulator 9 toward reservoir 16, when the pressure in this accumulator is, for certain positions of piston 8, higher than the pressure existing in said reservoir 16.

In this way, I obtain a regulation of the return energy supplied by accumulator 9, whereby this energy is automatically varied in accordance with the pressure existing in casing 7 and of the mean pressure in accumulator 9.

In order to obtain, in the embodiment shown by Fig. 3, the control of slide valve 35 in accordance not only with the pressure existing in casing and with the mean pressure in accumulator 9, but also with the inlet or discharge pressure in main compression chamber 6¹, distributing valve 35 is controlled, on the one hand, by means of a piston 39¹ subjected, through calibrated conduit 44, to the action of the mean pressure existing in accumulator 9 and, on the other hand, by

means of a spring 47 the ends of which bear, respectively, against slide valve 35 and against a support 48, the tension of spring 47 being variable both by the pressure existing in casing 7 and by the pressure existing in reservoir 16.

For this purpose, said support 48 of one of the ends of spring 47 is subjected to the action of a cam 49 carried by a rod 50 the ends of which are rigid, respectively, with a piston 51 and a piston 52. The first of these pistons, to wit 51, is movable in a cylinder 53 under the action of the pressure existing in reservoir 16, while the second piston, to wit 52, is movable in a cylinder 54 under the action, on the one hand, of the mean pressure existing in casing 7 (which pressure is transmitted to cylinder 54 through a calibrated orifice 55) and, on the other hand, of a spring 56.

I will now proceed to describe a third embodiment of my invention, shown in Fig. 4, in which the compressor part of the motor-compressor, instead of compressing separately the air to be fed to a storage reservoir such as 16 and that to be fed to the motor cylinder of the machine, simultaneously performs both of these compression actions and delivers a single stream of air a portion of which is sent to the reservoir while the remainder is fed to the motor cylinder after partial expansion, for instance in a receiver such as a turbine.

In this embodiment of the invention, the air from the atmosphere passes through a blower 60 which discharges it with a certain pressure into the inlet chamber 61 of compressor cylinder 59, which constitutes the compressor part of the motor-compressor. This compressor cylinder is of the double acting type. This air, after compression in said cylinder, issues therefrom through conduit 62.

A portion of this compressed air is sent to reservoir 16 through a conduit 67 branching off from conduit 62. The remainder is fed through 62 to a turbine 63 which is thus operated by said air so as to supply any desired useful work. The air in question undergoes in turbine 63 but a partial expansion so that when it leaves turbine 63 through conduit 64 it is still at a certain pressure. Accordingly this air can be fed through conduit 64 to the motor cylinder 57 of the motor-compressor, where it acts to scavenge and to supercharge said motor cylinder.

The exhaust gases leaving motor cylinder 57 pass through conduit 65, which leads them to turbine 66 which they operate and from which they escape into the atmosphere. This turbine 66 is mechanically connected with blower 60 which feeds compressed air to compressor cylinder 59, whereby said blower 60 is driven by turbine 66.

It should be noted that, in the embodiment illustrated by Fig. 4, there is a single gaseous circuit, including blower 60, cylinder 59, conduit 62, turbine 63, motor cylinder 57, conduit 64 and turbine 66, from which the gaseous stream is returned to the atmosphere.

In the embodiment of Fig. 4, the means for regulating the air cushion in accumulator cylinder 58 are exactly the same as described with reference to Fig. 3, the same elements being designated by the same reference characters. Cylinder 53 is in communication with reservoir 16 and cylinder 54 is in communication with the inside of motor cylinder 57 through orifice 55.

In a general manner, while I have, in the above description, disclosed what I deem to be practical and efficient embodiments of the present

invention, it should be well understood that I do not wish to be limited thereto as there might be changes made in the arrangement, disposition and form of the parts without departing from the principle of the present invention as comprehended within the scope of the appended claims.

What I claim is:

1. A motor-compressor which comprises, in combination, a motor part including a motor cylinder and a motor piston freely movable in said motor cylinder, a compressor part including a compressor cylinder and a compressor piston movable therein and operatively connected with said motor piston, pre-compression means operative by said motor piston for feeding air under pressure to said motor cylinder, means for supercharging said compressor part, means for supercharging said pre-compression means including a blower, a gas-turbine, adapted to be fed by the exhaust gases from said motor cylinder, mechanically connected with said blower for driving it, and means for varying the power of said turbine in response to variations of the pressure of the air compressed by said compressor part, and inversely to said variations.

2. A motor-compressor which comprises, in combination, a motor part including a motor cylinder and a motor piston freely movable in said motor cylinder, a compressor part including a compressor cylinder and a compressor piston movable therein and operatively connected with said motor piston, pre-compression means operative by said motor piston for feeding air under pressure to said motor cylinder, means for supercharging said compressor part, means for supercharging said pre-compression means including a blower, a gas-turbine, adapted to be fed by the exhaust gases from said motor cylinder, mechanically connected with said blower for driving it, and means for varying the power of said turbine in accordance with one of the operating pressures of said compressor part.

3. A motor-compressor which comprises, in combination, a motor part including a motor cylinder with an exhaust port and a motor piston freely movable in said motor cylinder, a compressor part including a compressor cylinder and a compressor piston movable therein and operatively connected with said motor piston, pre-compression means operative by said motor piston for feeding air under pressure to said motor cylinder, means for supercharging said pre-compression means and said compressor part, the

means for supercharging said precompression means including a blower, a gas-turbine, adapted to be fed by the exhaust gases from said motor cylinder, mechanically connected with said blower for driving it, conduit means connecting the exhaust port of said motor cylinder with the intake of said turbine, valve means for controlling the cross section of said conduit means, and means responsive to variations of the discharge pressure in said compressor part for operating said valve means.

4. A motor-compressor which comprises, in combination, a motor part including a motor cylinder with an exhaust port and a motor piston freely movable in said motor cylinder, a compressor part including a compressor cylinder and a compressor piston movable therein and operatively connected with said motor piston, pre-compression means operative by said motor piston for feeding air under pressure to said motor cylinder, means for supercharging said pre-com-

pression means, the means for supercharging said pre-compression means including a blower, a gas-turbine, adapted to be fed by the exhaust gases from said motor cylinder, mechanically connected with said blower for driving it, conduit means connecting the exhaust port of said motor cylinder with the intake of said turbine, valve means for controlling the cross section of said conduit means, and means responsive to variations of one of the operating pressures of said compressor part for operating said valve means.

5. A motor-compressor which comprises, in combination, a motor part including a motor cylinder with an exhaust port, and a motor piston freely movable in said motor cylinder, a compressor part including a compressor cylinder and a compressor piston movable therein and operatively connected with said motor piston, pre-compression means operative by said motor piston for feeding air under pressure to said motor cylinder, means for supercharging both of said pre-compression means and said compressor part in parallel, said supercharging means including a blower, a gas turbine, adapted to be fed by the exhaust gases from said motor cylinder, mechanically connected with said blower for driving it, conduit means connecting the exhaust port of said motor cylinder with the intake of said turbine, valve means for controlling the cross section of said conduit means, and means responsive to variations of the discharge pressure in said compressor part for operating said valve means so that said cross section is minimum when said discharge pressure is minimum and increases when said discharge pressure increases.

6. A motor-compressor which comprises, in combination, a motor part including a motor cylinder and motor piston means freely movable in said motor cylinder, a compressor part including a compressor cylinder and a compressor piston movable therein and operatively connected with said motor piston means, pre-compression means operative by said motor piston for supplying air under pressure to said motor cylinder, means for supercharging both of said pre-compression means and said compressor part, said supercharging means including a blower, and a gas turbine, adapted to be fed by the exhaust gases from said motor cylinder, mechanically connected with said blower for driving it, a pressure accumulator including a cylinder and a piston movable therein, with a mass of air entrapped therebetween, said last mentioned piston being connected with said motor piston means in positive mechanical manner, a source of gas under pressure, a slide valve for connecting the inside of said accumulator cylinder either with said source or with the atmosphere, means operative by the mean pressure in said accumulator cylinder for urging said slide valve in the direction corresponding to the connecting of said accumulator with the atmosphere, and means operative by the discharge pressure of said pre-compression means, for urging said slide valve in the direction corresponding to the connecting of said accumulator cylinder with said source of gas under pressure.

7. A motor-compressor which comprises, in combination, a motor part including a motor cylinder and motor piston means freely movable in said motor cylinder, a compressor part including a compressor cylinder and a compressor piston movable therein and operatively connected with said motor piston means, pre-compression

means operative by said motor piston for supplying air under pressure to said motor cylinder, means for supercharging said pre-compression means, said supercharging means including a blower, and a gas turbine, adapted to be fed by the exhaust gases from said motor cylinder, mechanically connected with said blower for driving it, a pressure accumulator including a cylinder and a piston movable therein, with a mass of air entrapped therebetween, said last mentioned piston being connected with said motor piston means in positive mechanical manner, means operative on the one hand by the mean pressure in said accumulator cylinder, and on the other hand by the discharge pressure of said pre-compression means for varying the amount of gas in said pressure accumulator.

8. A motor-compressor which comprises, in combination, a motor part including a motor cylinder and motor piston means freely movable in said motor cylinder, a compressor part including a compressor cylinder and a compressor piston movable therein and operatively connected with said motor piston means, an arrangement for superfeeding the motor part and the compressor part including a rotary blower, a gas turbine operatively connected with said blower and means for feeding exhaust gases from said motor cylinder to said turbine, a pressure accumulator including a cylinder and a piston movable therein, with a mass of air entrapped therebetween for assuring the return strokes of said motor and compressor pistons, said last mentioned piston being connected with said motor piston in positive mechanical manner, means operative on the one hand by the mean pressure in said accumulator cylinder and on the other hand by the feeding pressure of said motor cylinder for varying the amount of gas in said pressure accumulator.

9. A motor-compressor which comprises, in combination, a motor part including a motor cylinder and a free piston operating in said cylinder, a compressor part including a compressor cylinder and a compressor piston operating in said compressor cylinder and operatively connected to the motor piston, said two pistons forming a unidirectional unit insofar as the motive stroke is concerned, an arrangement for superfeeding the motor part and the compressor part, such arrangement including a rotating blower and a gas turbine, means for feeding to said turbine at least for certain conditions of operation of the motor-compressor the whole of the exhaust gas of the motor cylinder, means mechanically connecting the turbine with the blower to drive the latter, a pneumatic energy accumulator acting on said piston unit to assure its return strokes, and means responsive to variations in at least one of two pressures, to wit that of the gas entering the motor cylinder and that of the gas delivered by the compressor cylinder, to vary the quantity of gas in said accumulator.

10. A motor-compressor which comprises, in combination, a motor part including a motor cylinder and a motor piston freely movable in said motor cylinder, a compressor part including a compressor cylinder and a compressor piston movable therein and operatively connected with said motor piston, pre-compression means operative by said motor piston for supplying air under pressure to said motor cylinder, means for supercharging said pre-compression means including a blower, a gas turbine, adapted to be fed by the exhaust gases from said motor cylinder.

der, mechanically connected with said blower for driving it, a receiver machine interposed between the discharge of said compressor part and the intake thereof, whereby air under pressure supplied by said compressor part performs a certain amount of work in said receiver machine, where it expands, and returns to said compressor part to be again compressed, the parts through which said air thus circulates forming a closed circuit, and means for varying the weight of air in this circuit so as correspondingly to modify the mean pressure in said closed circuit.

11. A motor-compressor which comprises, in combination, a motor part including a motor cylinder and motor piston means freely movable in said motor cylinder, a compressor part including a compressor cylinder and a compressor piston movable therein and operatively connected with said motor piston means, a pre-compression means operative by said motor piston for supplying air under pressure to said motor cylinder, a receiver machine interposed between the discharge of said compressor part and the intake thereof, whereby air under pressure supplied by said compressor part performs a certain amount of work in said receiver machine, where it expands, and returns to said compressor part to be again compressed, the parts through which said air thus circulates forming a closed circuit, and means for varying the weight of air in this circuit so as correspondingly to modify the mean pressure in said closed circuit, means for supercharging said pre-compression means including a blower, a gas turbine, adapted to be fed by the exhaust gases from said motor cylinder, mechanically connected with said blower for driving

it, conduit means connecting the exhaust port of said motor cylinder with the intake of said turbine, valve means for controlling the cross section of said conduit means, and means responsive to variations of the pressure in said closed circuit of the compressor part for operating said valve means so that said cross section is minimum when said pressure in the closed circuit is maximum and inversely.

10 12. A motor-compressor according to claim 11, further including a pneumatic energy accumulator operatively connected with a motor piston for producing the return strokes thereof, and means for varying the amount of gas in said accumulator according both to the pressure in said compressor part and the pressure in said pre-compression means.
